CLAIM

The ornamental design for a feeding station, as shown and described.

DESCRIPTION

FIG. 1 is a front, top, right perspective view of a feeding station, showing the new design;

FIG. 2 is a rear, bottom, left perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top plan view thereof; and,

FIG. 8 is a bottom plan view thereof.

The broken lines illustrate portions of the feeding station that forms no part of the claimed design.

1 Claim, 8 Drawing Sheets
